UNITED STATES PATENT OFFICE.

CHARLES A. UFFORD, OF DORCHESTER, MASSACHUSETTS.

DRESS FORM.

Application filed October 30, 1926. Serial No. 145,297.

This invention relates to sectional dress forms and has for its object to provide a novel means for adjusting the size of the dress form at the waist line by which the 5 operation of effecting the adjustment may be facilitated and may be accomplished without the necessity of reaching into the interior of the form through the armholes to loosen or tighten the nuts or clamping screws. 10 In accomplishing the object of the invention I provide an actuating member which extends upwardly through the neck of the form and is vertically movable relative to the form and also provide a novel connection between said 15 member and the form at the waist line, whereby when said member is raised the dress form will be contracted at the waist line and when said member is lowered the dress form will be expanded. Since this vertically movable member can be actuated from above the 20 form the operation of expanding or contracting the waist line is greatly simplified and made extremely easy.

In order to give an understanding of the 25 invention I have illustrated in the drawings a selected embodiment thereof which will now be described after which the novel features will be pointed out in the appended claims.

30 Fig. 1 is a vertical section through a dress form embodying my invention and showing said dress form contracted;

Fig. 2 is a similar view showing the dress 35 form expanded;

Fig. 3 is a section on the line 3—3, Fig. 1;

Fig. 4 is a section on the line 4—4, Fig. 1;

Fig. 5 is an enlarged vertical sectional view 40 through the neck.

The dress form shown in Figs. 1 to 5 is indicated generally at 1 and it is divided in a familiar way to form four neck sections 2, eight bust sections 3 and eight hip sections 4, this being a common way of dividing a dress form. The bust sections and hip sections are 45 hinged together by suitable hinge connections 5 as usual and the hip sections are adjustably secured at their lower ends to a cruciform member 6 which is adjustably mounted on the stand 7. The connection between the hip sections and the member 6 is, or may be, all as shown in my Patent No. 1,504,456, dated August 12, 1924.

50 Each hip section 4 is formed with an inwardly-directed connecting plate 8, said plates being slotted and being connected to the

slotted arms of the cruciform member 6 by means of clamping bolts 9.

The bust members 3 are connected together so as to permit them to expand and contract. Every other bust member has connected thereto two slotted straps 10 which extend in opposite directions, each strap overlying the adjacent section. Each of the other sections has a screw-threaded stud 11 anchored therein which extends through the slots of the 60 overlying straps 10 and if desired each stud may carry a clamping nut 12 for retaining the straps on the studs. It is not intended, however, that these clamping nuts should be set up tight as it is desirable that the straps 65 should be free to slide one on the other as the form is expanded or contracted.

Extending vertically through the form is an actuating member 13 in the form of a rod, the lower end of which telescopes into the 70 tubular stand 7 and the upper end of which extends up through the neck of the form and projects above the form. This actuating member 13 is so connected to the form at the

waist line that the raising of the actuating 75 member will contract the form and the downward movement of said member will expand the form. In Figs. 1 and 2 the connection between the actuating member and the dress

form is in the form of a lazy-tongs device 14, 80 the lower end of said device being connected to two of the hip sections 4 immediately adjacent the waist line. This lazy-tongs structure comprises a series of pivotally-connected

links, the upper links of which are pivoted 85 to the actuator at 15. The lower ends 19 and 20 of the lower arms or links of the lazy-tongs structure are pivoted at 16 and 17 re-

spectively to the front and rear hip sections 4, 90 each of these hip sections having an ear 18 secured thereto to which the link is pivoted. 95

With this construction it will be seen that when the actuator 13 is raised relative to the form the lazy-tongs structure will be extended 100 vertically with the result that the lower ends 19 and 20 of the lower links will be drawn together as shown in Fig. 1 thus pulling the front and rear hip sections inwardly. This

movement will have a tendency to contract the 105 entire form at the waist line because of the loose connection between the connecting straps 10. On the other hand, if the actuator

110 is moved downwardly relative to the form as shown in Fig. 2 the resultant downward movement of the upper end of the lazy-tongs

relative to the lower end will contract the lazy-tongs structure and thus force the lower ends 19, 20 of the lower links outwardly thus forcing the front and rear hip sections away 5 from each other. This will have a tendency to expand the form at the waist as will be obvious. The lower arm of the lazy-tongs which is connected to the rear of the form is shorter than that connected to the front of 10 the form as shown in Figs. 1 and 2. The advantage of this is that it tends to keep the form in proper position as it is expanded and contracted.

If when the actuator is manipulated to contract the form the upper hip sections to which the lazy-tongs is secured are contracted or pulled inwardly to a greater extent than the other sections the proper symmetry of the 15 form may be secured by simply pressing generally inwardly at the sides of the form. The loose connection of the overlapping straps 10 permits this correction to be made readily. Similarly, if when the actuating member is forced downwardly to expand the form it is 20 found that the front and rear hip sections are pushed outwardly to a greater extent than the side sections, the required symmetry of the form may be readily secured by simply pulling outwardly on the side sections. 25

30 Means are provided for locking the actuating member 13 in any adjusted position. As herein shown said actuating member extends up through a sleeve 21 to which the neck sections are clamped, said sleeve carrying a 35 clamping screw 22 for the purpose of clamping the actuating member 13 in its desired position. When the clamping screw 22 is loosened the actuator 13 may be easily moved up or down while when the adjustment has 40 been secured it may be maintained by tightening up the clamping screw 22.

Each of the neck sections has the usual plate 23 extending inwardly therefrom, said plates overlapping each other and each provided with a slot through which the sleeve 45 21 extends. This sleeve is formed on its lower end with a collar 24 and has screw-threaded thereto a clamping collar 25. When the clamping collar 25 is screwed down the neck 50 section plates will be clamped together in their adjusted position.

In Fig. 2 the dress form is shown expanded not only at the waist but also at the hips, the hip adjustment being secured by 55 loosening the clamping bolts 9. If it is desired to expand or contract the waist without adjusting the hips this may be done simply by manipulating the actuator 13. If, however, an adjustment at the hips is required 60 as well as at the waist then, of course, the clamping screws 9 will have to be loosened. However, since the nuts on these clamping screws 9 are situated on the under side they can be readily reached.

65 I find it desirable to so connect the bust sec-

tions to the hip sections as to leave a slight space between said sections as this will permit the sections to be drawn inwardly or forced outwardly at the waist line without binding.

In the construction shown in Figs. 1 and 2 the lazy-tongs device is connected to the front and rear of the form only. With this construction when the actuating member is moved up or down the form will be expanded or contracted at the front and rear and then some manual manipulation may be required to properly adjust the form at the sides.

70 My improvements thus provide for adjusting the form at the waist line without the necessity of reaching into the form to loosen or tighten a series of nuts or screws.

I claim:

1. A dress form comprising a plurality of sections adjustable relative to each other, a 85 tubular stand on which said dress form is mounted, an actuating rod telescoping into said stand and extending above the neck of the latter, and a plurality of links pivotally connected together to form a lazy-tongs device which is pivotally connected at its upper end to said rod and at its lower end to the waist portion of the form, whereby said waist portion may be expanded or contracted by vertical movement of the actuator.

2. A dress form divided vertically in a plurality of places, straps loosely connecting the sections at the waist line to permit them freely to expand and contract, a rod extending vertically through the form and above the neck of the latter, said rod being vertically movable relative to the form, a plurality of links connected to form a lazy-tongs structure, said structure being pivotally connected at its upper end to the rod and having its lower end pivotally connected to the dress form at the waist line, whereby vertical movement of the rod will operate to expand or contract the form.

3. A dress form divided vertically in a plurality of places to provide sections adjustable relative to each other, straps loosely connecting the sections at the waist line, a rod extending vertically through the form and above the latter, said rod being vertically movable relative to the form, a lazy-tongs structure connected at its upper end to said rod and the lower end presenting two arms which are pivoted to the front and rear of the form at the waist thereof, whereby vertical movement of the rod will operate through the lazy-tongs connection to cause the form to expand or contract at the waist.

4. A dress form divided vertically in a plurality of places, straps loosely connecting the sections at the waist line to permit them to freely expand and contract, a vertically movable actuator extending through the form and above the latter, a lazy-tongs connection

between said actuator and the dress form at the waist line, whereby vertical movement of the actuator will operate to expand or contract the form, a sleeve at the neck portion 5 through which the actuator extends, and means for clamping the actuator to the sleeve in any adjusted position.

5. A dress form divided vertically in a plurality of places to form a plurality of sections, means loosely connecting the sections 10 at the waist line to permit them freely to expand and contract, a vertically movable actuator extending through the form and

above the latter, a lazy-tongs member pivotally connected at its upper end to said actuator, the lower end of said lazy-tongs member presenting two arms, one of which is pivotally attached to the front of the form at the waist line and the other of which is pivotally attached to the rear of the form, the 15 latter arm being shorter than the former arm.

In testimony whereof, I have signed my name to this specification.

CHARLES A. UFFORD.
